(57) **CLAIM**

The ornamental design for a debris-pan attachment for push-broom, as shown and described.

DESCRIPTION

FIG. 1 is a top-rear perspective view of a debris-pan attachment for push-broom in accordance with the present invention;

FIG. 2 is a rear elevation thereof, illustrated coupled to a push broom;

FIG. 3 is a front elevation thereof;

FIG. 4 is a right side elevation thereof;

FIG. 5 is a left side elevation thereof;

FIG. 6 is a top-right perspective view thereof;

FIG. 7 is a top view thereof;

FIG. 8 is a bottom view thereof; and,

FIG. 9 is an exploded top-rear perspective view thereof.

The broken lines in the drawings represent an unclaimed push broom and form no part of the claim.
